LUBRICATING APPARATUS

Edgar L. Finch, Glendale, Calif., assignor to
B. F. B. Engineers, Incorporated, a corporation
of California

Application June 25, 1943, Serial No. 492,209

3 Claims. (Cl. 184—55)

This invention relates to a lubricating apparatus.

The general object of the invention is to provide an improved method and apparatus by means of which lubricant will be supplied to a pneumatically operated tool such as a hammer, riveter, etc.

A more specific object of my invention is to provide an improved means for introducing a lubricant into the compressed air being supplied to a pneumatic tool.

A further object of my invention is to provide a novel pulsating lubricator.

An additional object of my invention is to provide a novel lubricator including a member which pulsates under various pressure conditions of the fluid in which the member is immersed and in performing the pulsating action causes slight quantities of material to be released into the fluid.

Other objects and advantages of my invention will be apparent from the following description taken in connection with the accompanying drawings wherein:

Fig. 1 is a side elevation of a pulsating lubricating apparatus embodying the features of my invention;

Fig. 2 is a central sectional view through the lubricator;

Fig. 3 is a central sectional view through the capsule;

Fig. 4 is a section taken on line 4—4, Fig. 2;

Fig. 5 is a section taken on line 5—5, Fig. 2;

Fig. 6 is a fragmentary central sectional view, with parts in elevation, showing a modification of my invention;

Fig. 7 is an elevation, with parts in section, showing a further modification;

Fig. 8 is a side elevation, with parts in section, showing a further modification, and

Fig. 9 is a section taken on line 9—9, Fig. 8.

Referring to the drawings by reference characters, I have shown my invention as embodied in a pulsating lubricating apparatus which is indicated generally at 10. My apparatus is particularly adapted for lubricating the working parts of pneumatic tools such as pneumatic riveters, hammers, etc. Tools of this nature are operated by compressed air from a suitable source, usually by means of a flexible hose, and my invention is arranged in some portion of the conduit between the source of compressed air and the working part of the tool.

In Figs. 1 to 5, inclusive, my apparatus is arranged in the hose portion of the conduit. This

hose, indicated at 11, engages the ends 12 of a body 13. The hose ends are held in place by suitable clamps 14. The body 13 includes a hollow, transparent, cylindrical main portion 15 and an end portion 16 threaded as at 17 to the main portion 15. The ends 12 are provided with apertures 18 while the main portion 14 has a central bore 19 communicating with the apertures 18. At the inner end of the member 16 and the inner end of the bore 19 remote therefrom spaced inwardly directed pins 20 prevent a capsule 21 from impeding flow through the conduit.

The capsule 21 may be made of any suitable material, such as gelatin or various plastics, and it comprises an inner member 22 and an outer member 23 which have ends 24 and 25 respectively. The portions 22 and 23 telescope and slide one upon the other. The end 25 is provided with an aperture 26 through which the end 27 of a wick member 28 extends. The capsule 21 receives a charge of lubricant 29.

In use, the capsule 21 is placed in the bore 19 and the pneumatic tool is used in the usual manner. When tools of this character are connected to the service line pressure builds up in the conduit when the tool is not operating. As soon as the tool starts operation the pressure drops somewhat thus decreasing the pressure in the bore 19. When the operation of the tool is stopped the pressure in this bore again increases. As a result the pressure within the bore 19 is continually changing and thus the pressure on the capsule constantly changes. This causes a very slight relative longitudinal movement between the parts 22 and 23. The lubricant 29 enters the location 30 (Fig. 3) between the overlapping ends of the capsule and the lubricating oil gradually works outwardly and each time the slight telescopic movement occurs a small amount of oil is wiped along the part 22 by the end 31 on the member 23. This action is somewhat similar to the action of a piston ring on a piston.

The air passing through the bore 19 engages the oil on the portion 22 of the capsule and thus small quantities of oil are carried by the compressed air to the working parts of the tool. The exposed end 27 of the wick becomes moistened with the oil and the air passing over this portion takes some of the oil from the wick end 27.

In Fig. 6 the body member 40 has a threaded end 41 which directly engages a threaded portion 42 on the body 43 of the pneumatic tool. 55 The body 40 is similar to the body 13 except that

at one end it has a transverse pin 44 to limit the movement of the capsule 45 instead of having the pins 20 at both ends. The body 40 is closed by a member 46 which is similar in all respects to the member 16 previously described except that its end is threaded as at 47 and is connected by a coupling 48 to the conduit portion 49 to which a valve control member 50 is connected. The particular construction of the parts 49 and 50 form no part of the present invention. The capsule 45 is similar in all respects to the capsule 21 previously described except that it is shown as shorter and of somewhat greater diameter relative to its length.

In Fig. 7 the body 50 of a pneumatic tool has a conduit 51 therein and in this conduit I arrange a capsule 52 similar in all respects to the capsules 21 and 45 previously described. The conduit 51 has a transverse bar 53 to limit movement of the capsule 52 in one direction. The conduit 51 is connected by a fitting 54 to a coupling 55. The coupling 55 is connected to another portion of the conduit shown as a hose 56. The fitting 54 is clamped by a collar 57 upon a threaded neck 58 on the body 50. A transverse pin 59 in the fitting 54 limits the movement of the capsule 52 in a direction away from the tool 50.

The body portion 50 is provided with a threaded aperture 60 in which a transparent plug 61 is secured. This plug being transparent the operator can observe the capsule 52 and determine when the oil has been used up.

In Figs. 8 and 9 a conduit 65 includes fittings 66 which connect it with a body 67 which has a bore 68 therein. The bore 68 is connected by conduits 69 and 70 with an offset conduit 71. The conduit 69 includes a valve 72 which has an operating stem 73 (Fig. 9) thereon by means of which communication from the conduit 69 may be controlled.

The bore 68 includes a protuberance 74 which tends to restrict passage through the bore 68 so that when the valve 72 is opened a portion of the compressed air in the conduit 65 will pass through the bore 69 into the conduit 71 and thence to the conduit 70.

Within the conduit 71 I provide a lubricating member 75. This member may be made of compressed fiber, cotton, or other oil absorbing material and it is so designed that the compressed air passing over the member 75 will take up some of the oil therefrom and thus carry this oil to the working parts of a tool which is connected to the conduit 65.

From the foregoing description it will be apparent that I have invented a novel pulsating lubricating apparatus which can be economically manufactured and installed and which is highly efficient for its intended purpose.

Having thus described my invention, I claim:

1. A lubricator comprising an elongated,

hollow member having a bore therethrough and a lubricant container in said bore and comprising a pair of hollow telescopic members adapted to readily slide one upon the other and adapted to contain a lubricant, said lubricant container being free for movement in said bore, and means adapted to connect the lubricator to an air passageway of a pneumatic tool to be lubricated so that an increase of air pressure in the bore will cause said telescopic members to move together to thereby discharge lubricant between the overlapping ends of the telescopic members.

2. A lubricator comprising an elongated, hollow, cylindrical member having a main bore and having a reduced bore at one end communicating with the main bore, the body at the other end being internally threaded, an end portion having a reduced threaded portion engaging the threads in said body, said end portion having a reduced bore therein communicating with the main bore, and a lubricant container in said main bore and comprising a pair of hollow telescopic members adapted to readily slide one upon the other and adapted to contain a lubricant, said lubricant container being free for movement in said main bore, and means adapted to connect said member to an air passageway of a pneumatic tool to be lubricated so that an increase of air pressure in the main bore will cause said telescopic members to move together to thereby discharge lubricant between the overlapping ends of the telescopic members.

3. A lubricator comprising an elongated, hollow, transparent cylindrical member including a body having a main bore and having a reduced bore at one end communicating with the main bore, the body at the other end being internally threaded, an end portion having a reduced threaded portion engaging the threads in said body, said end portion having a reduced bore therein communicating with the main bore, said end portion and said body having spaced integral pins extending into said body bore, and a lubricant container in said main bore and comprising a pair of hollow telescopic members adapted to readily slide one upon the other and adapted to contain a lubricant, one of said telescopic members being imperforate, the other telescopic member having an aperture therein, a wick arranged in said aperture and extending from a point without said other telescopic member to a point within said other telescopic member, said lubricant container being free for movement as a unit in said main bore, and means adapted to connect said member to an air passageway of a pneumatic tool to be lubricated so that an increase of air pressure in the main bore will cause said telescopic members to move together to thereby discharge lubricant between the overlapping ends of the telescopic members.

EDGAR L. FINCH.
